(57) **CLAIM**

The ornamental design for a travel pillow, as shown and described.

DESCRIPTION

FIG. 1 is a first isometric view of a new ornamental design for a travel pillow, arranged in a first configuration and showing a front of the travel pillow, and showing the novel design.

FIG. 2 is a second isometric view of the new ornamental design for the travel pillow, arranged in the first configuration and showing a rear of the travel pillow showing the novel design.

FIG. 3 is a front view of the new ornamental design for the travel pillow, arranged in the first configuration, and showing the novel design.

FIG. 4 is a rear view of the new ornamental design for the travel pillow, arranged in the first configuration, and showing the novel design.

FIG. 5 is a first side view of the new ornamental design for the travel pillow, arranged in the first configuration, and showing the novel design.

FIG. 6 is a second side view of the new ornamental design for the travel pillow, arranged in the first configuration, and showing the novel design.

FIG. 7 is a bottom view of the new ornamental design for the travel pillow, arranged in the first configuration, and showing the novel design.

FIG. 8 is a top, plan view of the new ornamental design for the travel pillow, arranged in the first configuration, and showing the novel design; and,

FIG. 9 is a third isometric view of the new ornamental design for the travel pillow, arranged in a second, folded configuration, and showing the novel design.

The shade lines in the Figures show contour and not surface ornamentation. The stipple texture in FIGS. 2 and 4 shows the contrast of appearance of a hook and loop fastener forming part of the claimed design.
